(57) **CLAIM**

The ornamental design for an ankle and pull buoy for swim training, as shown and described.

DESCRIPTION

FIG. 1 is a bottom left perspective view of an ankle and pull buoy for swim training showing our new design;

FIG. 2 is a front elevational view thereof, the rear elevational view being an identical mirror image thereof;

FIG. 3 is a right side elevational view thereof, the left side elevational view being an identical mirror image thereof;

FIG. 4 is a top plan view thereof; and,

FIG. 5 is a bottom plan view thereof.

The broken lines shown in FIG. 1 represent environmental subject matter and form no part of the claimed design.
